SHOE AND ARCH SUPPORTER THEREFOR

Claude H. Daniels, Wellesley Hills, Mass.

Application May 27, 1933, Serial No. 673,281

18 Claims. (Cl. 36—76)

My present invention relates to boots and shoes, and more particularly to boots or shoes wherein is incorporated a metallic arch stiffener or supporter, and the instant invention includes also the novel stiffener or arch supporter per se as an article of manufacture.

An important object of the present invention is the provision of a boot or shoe which will have incorporated therein an efficient longitudinal arch supporter.

A further feature of my invention resides in so constructing and assembling my novel shoe and arch supporter that said shoe will have a self-locking arch therein, this valuable feature being created entirely by the novel details of construction of my novel arch supporter or shank stiffener.

An important result of this self-locking arch is the fact that the stiffener, when the weight of the wearer is placed thereon, will be forced or pressed toward the longitudinal arch of the foot, instead of bending or flexing away therefrom, and thus the wearer of shoes in which my novel arch supporter is incorporated is assured of a constant and entirely automatic arch support.

Another object of the invention resides in the particular construction of arch supporter utilized. The body of this arch supporter may be of any desired size, shape, design or style. That herein illustrated is of the well-known cottage shank type, with the important exception of the forward end thereof which is under the ball of the foot. This forward end of the supporter is curved or spooned, longitudinally but not laterally, the extreme forward end of said spoon or tongue being preferably beveled on its under surface in such manner as to leave a sharp, biting upper edge.

Because of the curve of the tongue, and the inherent resilience of the material of which said supporter is constructed, this sharp edge will be in constant engagement with the under surface of the insole. When the weight of the wearer, or the pressure of the foot, is exerted on the shoe, this sharp edge will "bite" into the said under surface of the insole, automatically locking the supporter in position, the rearward end of said supporter being provided with suitable holding means.

A further and important feature of my present invention resides in the provision of wings, at each side of the forwardly projecting tongue, and but slightly spaced therefrom, said wings being normally on a plane slightly above the normal

horizontal plane of the curved portion of said tongue. Another important characteristic of these wings is the fact that said wings afford a far greater bearing surface for the forward end of the supporter against the outsole than would be possible if the tongue alone were utilized without said wings. Furthermore, the construction of the forward end of my novel supporter, as will be readily apparent to those skilled in this art, enables the said forward end of this supporter to more readily conform to the shape of the outsole and thus more efficiently and satisfactorily carry out its function of supporting the longitudinal arch of the foot when said supporter is automatically locked in position as above briefly explained. The above mentioned wings extend sufficiently far forward in the shoe to be located under the ball portion thereof, at each side of the spooned tongue, and thus my novel supporter presents to the fullest extent, a complete support, not only for the longitudinal arch of the foot, but also for the transverse or metatarsal arch.

The benefits and advantages of my novel supporter will be instantly apparent to those skilled in the art, and since I believe that said supporter, as well as the shoe in which same is incorporated, are novel, I have claimed the same in the present application.

All of the above, and other objects and features of the present invention, details of construction, and advantages, will be hereinafter more fully pointed out, described and claimed.

Referring to the drawing, illustrating a preferred embodiment of the invention,

Fig. 1 is a side elevation of a lady's pump, partially in section, with my novel supporter in position;

Fig. 2 is a vertical sectional view on the line 2—2 of Fig. 4;

Fig. 3 is a fragmentary longitudinal sectional view, on an enlarged scale, illustrating the forward end of the supporter, and its position in the shoe relative to the insole and outsole;

Fig. 4 is a top plan view of the arch supporter;

Fig. 5 is a side elevation of said supporter;

Fig. 6 is a front elevation of said supporter; and

Fig. 7 is a cross-sectional view on the line 7—7 of Fig. 1.

Referring now to the drawing, for a particular description of the invention, its construction and assembly, 1 designates the upper materials of a shoe, assembled on an insole 2 in the usual manner.

Before the outsole is affixed, my novel arch supporter 3 is applied to the shoe, the rearward

end of this supporter having a pair of apertures 4 therethrough, through which are driven tacks into the insole at the heel portion thereof, this being the only operation necessary to attach this 5 arch supporter to the shoe. This method of attaching the rear portion of my supporter to the shoe is optional, as the method of attaching constitutes no material part of the present invention. The shoe illustrated in the present application is 10 of the well-known McKay type, and subsequent to the arch supporter attaching operation, the outsole 5 is laid, temporarily secured to the insole, and then permanently attached thereto by through and through stitching, whereupon the heel 6 is attached. The outsole may be temporarily attached at the forward end before application or incorporation of the arch supporter, if desired.

The arch supporter illustrated has a curved 20 body portion constructed similar to the well known cottage shank supporter, but it will be appreciated and understood that the body portion of my novel supporter may be of any conventional design, shape, style or size, as the invention of the 25 present application is primarily directed to the forward end thereof, which will now be described.

The forward end 8 of the supporter is spooned 30 or curved in a direction reverse to the curve of the body, so that the general longitudinal contour of the central part of said supporter is that of a reverse curve. The extreme forward end of the tongue 8 is preferably squared, the under surface of this forward end being chamfered or beveled as illustrated at 9, leaving a sharp forward upper 35 edge 10.

Located at each side of the central tongue 8 is a wing 11, these wings extending forwardly with said tongue for a material portion of its length, but as will be apparent from an inspection of 40 Figs. 3 and 5, said wings are normally on a plane slightly above the normal horizontal plane of the tongue 8 at the lowermost part of its curve. These wings 11 extend forwardly under the ball of the foot, and constitute ample bearing for the supporter in the shoe, to prevent twisting, turning or other distortion thereof, and also constitute an additional support, not only for the longitudinal arch of the foot by reason of the increased 45 length thus added to the longitudinal arch supporting portion of the device, but also for the transverse or metatarsal arch by reason of their location under the metatarsal arch portion of the foot and the bearing and support thus afforded for said metatarsal arch, as clearly shown in Figs. 1, 5, 6 and 7. Furthermore, these wings 11 enable the supporter to more readily conform itself to the shape of the outsole, particularly when the 50 weight of the wearer is exerted thereon.

When positioned in the shoe, between the insole 2 and outsole 5, as clearly illustrated in Fig. 3, the spoon end 8 brings the sharp edge 10 into contact with the under surface of the insole 2 at the ball of the foot. Thus when the weight of the wearer is placed in a shoe, this will cause said edge 10 to bite into the under surface of the insole, locking the supporter in position between the attaching means at the rear portion thereof and the point at which the edge 10 of the tongue 8 has bitten into the insole.

The biting of the edge 10 into the insole 2 will 70 never be sufficient to penetrate through the insole, and thus cannot possibly injure the foot of the wearer. In prior shoes of this type, wherein the forward end of the shank stiffener was loose, and free to slide on action of the foot during walking,

the shank stiffener would be forced or pressed away from the arch of the foot, and thus would not have a constant arch supporting capacity.

In shoes where the forward end of the arch supporter has been fixed in position, the expense of manufacturing such shoes has been increased because of the additional operation or operations necessary to attach said forward end, and the attaching instrumentalities have frequently penetrated the insole, resulting in injury to the 10 wearer, damage to stockings, and other disadvantages. My present novel self-locking arch supporter obviates and eliminates all of these prior difficulties and disadvantages.

By my present invention, eliminating separate 15 attaching elements for the forward end of the arch supporter, I am enabled to more cheaply produce a shoe having a metallic arch supporter incorporated therein, while at the same time assuring the wearer of an automatically or self- 20 locked arch, and constant arch support, and these advantages will be fully understood and appreciated by those skilled in this art.

While I have necessarily described my present invention somewhat in detail, it will be appreciated that the showing of a McKay shoe is for 25 illustrative purposes only, and that I may vary the size, shape, style, type and design of my novel arch supporter or shank stiffener within reasonably wide limits without departing from 30 the spirit of the invention, or that this shank stiffener may be incorporated in a Goodyear welt shoe with equal facility, or incorporated in any type of shoe, between insole and outsole.

My invention is further described and defined 35 in the form of claims as follows:

1. In a boot or shoe, an insole, an outsole, a metallic arch supporter positioned therebetween, said supporter being permanently fixed to said shoe at its rear end only, the forward end of 40 said supporter terminating in an upwardly curved tongue having an edge on the upper forward end thereof, whereby, on pressure of the foot being applied in said shoe, said edge will bite into the under surface of the insole, and 45 automatically lock the supporter in position, and a forwardly projecting wing at each side of said tongue terminating short of the outer end thereof and being parallel therewith.

2. In a boot or shoe, an insole, an outsole, a 50 metallic arch supporter positioned therebetween, said supporter being permanently fixed to said shoe at its rear end only, the forward end of said supporter terminating at its central part in an upwardly curved tongue having an edge on the 55 upper forward end thereof, whereby, on pressure of the foot being applied in said shoe, said edge will bite into the under surface of the insole, and automatically lock the supporter in position, and a forwardly projecting wing at each side of 60 said tongue and parallel therewith.

3. In a boot or shoe, an insole, an outsole, a metallic arch supporter positioned therebetween, said supporter being permanently fixed to said shoe at its rear end only, the forward end of said supporter terminating in an upwardly curved tongue having an edge on the upper forward end thereof, whereby, on pressure of the foot being applied in said shoe, said edge will bite into the under surface of the insole, and automatically 70 lock the supporter in position, and a forwardly projecting wing at each side of said tongue, said wings being slightly spaced from and parallel with said tongue.

4. In a boot or shoe, an insole, an outsole, a 75

metallic arch supporter positioned therebetween, said supporter being permanently fixed to said shoe at its rear end only, the forward end of said supporter terminating in an upwardly curved tongue having an edge on the upper forward end thereof, whereby, on pressure of the foot being applied in said shoe, said edge will bite into the under surface of the insole and automatically lock the supporter in position, and a forwardly 5 projecting wing at each side of said tongue and parallel therewith, said wings extending for a substantial part of the length of said tongue and terminating short of the outer end thereof.

5. In a boot or shoe, an insole, an outsole, a metallic arch supporter positioned therebetween, said supporter being permanently fixed to said shoe at its rear end only, the forward end of said supporter terminating in an upwardly curved tongue having an edge on the upper forward end thereof, whereby, on pressure of the foot being applied in said shoe, said edge will bite into the under surface of the insole and automatically lock the supporter in position, and a forwardly 10 projecting wing at each side of said tongue, said wings being slightly spaced from said tongue and extending for a substantial part of the length of said tongue and also being normally above the normal horizontal plane of the 15 curved portion of said tongue.

6. In a boot or shoe, an insole, an outsole, a metallic arch supporter positioned therebetween, said supporter being permanently fixed to said shoe at its rear end only, the forward end of said supporter terminating in an upwardly curved tongue located under the metatarsal arch 20 and having an edge on the upper forward end thereof, whereby, on pressure of the foot being applied in said shoe, said edge will bite into the under surface of the insole and automatically lock the supporter in position, and a forwardly 25 projecting wing at each side of and parallel with said tongue, said wings extending sufficiently forward in said shoe to constitute additional supporting means for the metatarsal arch of the foot but terminating short of the outer end of said tongue.

7. In a boot or shoe, an insole, an outsole, a metallic arch supporter positioned therebetween, said supporter being permanently fixed to said shoe at its rear end only, the forward end of said supporter terminating in an upwardly curved tongue having an edge on the upper forward end thereof, whereby, on pressure of the foot being applied in said shoe, said edge will bite into the under surface of the insole and automatically lock the supporter in position, and a forwardly 30 projecting wing at each side of said tongue, said wings being slightly spaced from said tongue and being normally above the normal horizontal plane of the curved portion of said tongue.

8. In a boot or shoe, an insole, an outsole, a metallic arch supporter positioned therebetween, said supporter being permanently fixed to said shoe at its rear end only, the forward end of said supporter terminating in an upwardly curved tongue having an edge on the upper forward end thereof, whereby, on pressure of the foot being applied in said shoe, said edge will bite into the under surface of the insole and automatically lock the supporter in position, and a forwardly 35 projecting wing at each side of said tongue, said wings extending for a substantial part of the length of said tongue and being normally above the normal horizontal plane of the 40 curved portion of said tongue.

9. In a boot or shoe, an insole, an outsole, a metallic arch supporter positioned therebetween, said supporter being permanently fixed to said shoe at its rear end only, the forward end of said supporter terminating in an upwardly curved tongue having an edge on the upper forward end thereof, whereby, on pressure of the foot being applied in said shoe, said edge will bite into the under surface of the insole and automatically lock the supporter in position, and a forwardly 45 projecting wing at each side of said tongue, said wings being slightly spaced from said tongue and extending for a substantial part of the length of said tongue and also being normally above the normal horizontal plane of the 50 curved portion of said tongue.

10. In a boot or shoe, an insole, an outsole, a metallic arch supporter positioned therebetween, said supporter being permanently fixed to said shoe at its rear end only, the forward end of said supporter terminating in an upwardly curved tongue having its forward end beveled on its under side, thus forming a sharp biting edge on the upper forward end thereof, whereby, on pressure of the foot being applied in said shoe, 55 said edge will bite into the under surface of the insole and automatically lock the supporter in position, and a forwardly projecting wing at each side of said tongue.

11. In a boot or shoe, an insole, an outsole, a metallic arch supporter positioned therebetween, said supporter being permanently fixed to said shoe at its rear end only, the forward end of said supporter terminating in an upwardly curved tongue having its forward end beveled on its under side, thus forming a sharp biting edge 60 on the upper forward end thereof, whereby, on pressure of the foot being applied in said shoe, said edge will bite into the under surface of the insole and automatically lock the supporter in position, and a forwardly projecting wing at each side of said tongue, said wings extending for a substantial part of the length of said tongue.

12. A metallic arch supporter of the kind described, comprising a curved body portion, a forwardly projecting tongue bowed in a direction reverse to the curve of the body portion, and a forwardly projecting wing at each side of said tongue, said wings being parallel with and terminating short of the outer end of said tongue.

13. A metallic arch supporter of the kind described, comprising a curved body portion, a forwardly projecting tongue curved in a direction reverse to the curve of the body portion, the said curved tongue at its forward end being beveled 65 on its under surface to provide a sharp upper edge, and a forwardly projecting wing at each side of said tongue.

14. A metallic arch supporter of the kind described, comprising a curved body portion, a forwardly projecting tongue bowed in a direction reverse to the curve of the body portion, and a forwardly projecting wing at each side of said tongue, said wings being slightly spaced from said tongue and being normally above the normal horizontal plane of the curved portion of said tongue.

15. A metallic arch supporter of the kind described, comprising a curved body portion, a forwardly projecting tongue curved in a direction reverse to the curve of the body portion, the said curved tongue at its forward end being beveled 70 on its under surface to provide a sharp upper edge, and a forwardly projecting wing at each 75

side of said tongue, said wings extending for a substantial part of the length of said tongue.

16. A metallic arch supporter of the kind described, comprising a curved body portion, a forwardly projecting tongue curved in a direction reverse to the curve of the body portion, the said curved tongue at its forward end being beveled on its under surface to provide a sharp upper edge, and a forwardly projecting wing at each side of said tongue, said wings being slightly spaced from said tongue and being normally above the normal horizontal plane of the curved portion of said tongue.

17. In a boot or shoe, an insole, an outsole, a metallic arch supporter positioned therebetween, the forward end of said supporter terminating in an upwardly curved tongue having an edge on the upper forward end thereof, whereby, on pressure of the foot being applied in said shoe, said edge will bite into the under surface of the insole

and automatically lock the supporter in position, and a forwardly projecting wing at each side of and parallel with said tongue terminating short of the outer end thereof.

18. In a boot or shoe, an insole, an outsole, a metallic arch supporter positioned therebetween, the forward end of said supporter terminating in a curved tongue located under the metatarsal arch and having an edge on the upper forward end thereof, whereby, on pressure of the foot being applied in said shoe, said edge will bite into the under surface of the insole and automatically lock the supporter in position, and a forwardly projecting wing at each side of and parallel with said tongue, said wings extending sufficiently forward in said shoe to constitute additional supporting means for the metatarsal arch of the foot but terminating short of the outer end of said tongue.
